APPARATUS FOR CONTROLLING RAILWAY SWITCHES

Henry S. Young, Wilkinsburg, and Herbert L. Bone, Forest Hills, Pa., assignors to The Union Switch & Signal Company, Swissvale, Pa., a corporation of Pennsylvania

Original application December 10, 1935, Serial No. 53,774. Divided and this application October 31, 1936, Serial No. 108,646

4 Claims. (Cl. 246—3)

Our invention relates to apparatus for controlling railway switches, and particularly to apparatus for normally controlling a switch from a remote point, but for at times modifying such control in accordance with traffic conditions adjacent the switch.

Apparatus embodying our invention is particularly suitable for, although in no way limited to, the control of railway switches which are arranged to be operated by means of the switch operating mechanism described and claimed in an application for Letters Patent of the United States, Serial No. 40,606, filed by Herbert L. Bone, on September 14, 1935, for Railway switch operating apparatus.

The present application is a division of our copending application, Serial No. 53,774, filed on December 10, 1935, for Apparatus for controlling railway switches.

We will describe two forms of apparatus embodying our invention, and will then point out the novel features thereof in claims.

In the accompanying drawing, Fig. 1 is a diagrammatic view showing one form of apparatus embodying our invention. Fig. 2 is a view similar to Fig. 1 showing another form of apparatus embodying our invention.

Similar reference characters refer to similar parts in both views.

Referring first to Fig. 1, the reference characters 1 and 1^a designate the track rails of a stretch A of railway track, the one rail 1 of which is divided by means of insulated joints 2 to form a track section B—C. Located in section B—C is a switch E which connects the stretch A with a stretch of track F. The switch E is operated by a suitable switch mechanism M, which mechanism, as here shown, is of the electropneumatic type having included therein suitable biasing means for biasing the switch to its nearest extreme position whereby, when the switch is moved to either extreme position, it will be yieldably held in such extreme position even though the supply of fluid to the operating motor of the mechanism is then cut off. The mechanism M is provided with the usual normal magnet N and reverse magnet R, it being understood that the switch may be moved from its normal position to its reverse position by energizing the reverse magnet R, and from its reverse position to its normal position by energizing the normal magnet N. One form of mechanism which will operate in the manner just described is shown and described in an application for Letters Patent of the United States, Serial No. 40,606, filed by

Herbert L. Bone, on September 14, 1935, for Railway switch operating apparatus.

Operatively connected with the switch E is a circuit controller G comprising three movable contact fingers 45, 5, and 6 which cooperate respectively with fixed contact fingers 45^a 45^b, 5^a 5^b, and 6^a 6^b, to form contacts 45—45^a, 45—45^b, 5—5^a, 5—5^b, 6—6^a, and 6—6^b. Contacts 45—45^a and 6—6^a are closed when and only when switch E occupies its full normal position; contacts 45—45^b and 5—5^b are closed when and only when switch E occupies its full reverse position; contact 5—5^a is closed when switch E occupies any position but its full reverse position; and contact 6—6^b is closed when switch E occupies any position but its full normal position.

The apparatus also includes a manually operable lever L, a track relay D, two indication lamps H¹ and H², two resistors J¹ and J², and a battery K. The function of the lamps H¹ and H² and resistors J¹ and J² will become apparent as the description proceeds.

The lever L will usually be located at a point remote from the switch and, as here shown, is capable of assuming a normal position n and a reverse position r. Operatively connected with the lever L is a contact arm 7 which cooperates with two fixed contacts 7^a and 7^r to close a normal contact 7—7^a or a reverse contact 7—7^r according as lever L occupies its n or its r position. Also operatively connected with the lever L is a contact arm 21 which similarly cooperates with two fixed contacts 21^a and 21^r to close a normal contact 21—21^a or a reverse contact 21—21^r according as lever L occupies its n or its r position.

Relay D is controlled jointly by the lever L and by the circuit controller G in such manner that one pickup circuit for this relay will be closed when and only when the switch and lever both occupy their normal positions, and that another pickup circuit for this relay will be closed when and only when the switch and lever both occupy their reverse positions. The pickup circuit for relay D which is closed when and only when the switch and lever both occupy their normal positions passes from a track battery 3 through rail 1^a, wires 56 and 57, contact 45—45^a of circuit controller G, line wire 58, contact 21—21^a of lever L, wires 59 and 60, the winding of relay D, wire 61, and rail 1 back to battery 3. The other pickup circuit for relay D passes from battery 3 through rail 1^a, wires 56 and 57, contact 45—45^b of circuit controller G, line wire 62, contact 21—21^r of lever L, wires 59 and 60, the winding of relay D, wire 61, and rail 1 back to battery 3.

Relay D is further provided with a stick circuit which passes from battery 3 through rail 1^a, wire 56, front contact 63 of relay D, wire 60, the winding of relay D, wire 61, and rail 1 to battery 3.

5 It will be seen, therefore, that when relay D is once picked up, it will remain picked up by virtue of its stick circuit until a train enters section B-C, whereupon this relay will then become deenergized. It will also be seen that, when relay 10 D does become deenergized due to a train entering section B-C, this relay will subsequently remain deenergized until the train leaves the section and lever L is moved to the position corresponding to the position which the switch then 15 occupies.

20 The lever L and relay D jointly control the magnet valves N and R of the switch mechanism M in a manner which will become apparent from the following description of the operation of the apparatus as a whole.

25 As shown in the drawing, all parts are in their normal positions. That is to say, lever L and switch E both occupy their normal positions, and section B-C is unoccupied by a train. Under these conditions, magnets N and R are both deenergized and lamp H² is also deenergized. Lamp H¹, however, is lighted over a normal indication circuit which passes from battery K through wire 9, contact 7-7ⁿ of lever L, the filament of lamp H¹ connected in parallel with resistor J¹, front contact 10 of relay D, contact 6-6^a of circuit controller G, and wires 11 and 12 back to battery K.

30 We will now assume that the parts are in the 35 positions in which they are shown in the drawing, and that it is desired to reverse switch E. To do this, lever L is moved from its normal position *n* to its reverse position *r*, thus opening contacts 7-7ⁿ and 21-21ⁿ and closing contacts 40 7-7^r and 21-21^r. The opening of contact 7-7ⁿ interrupts the circuit which was previously closed for the indication lamp H¹ so that this lamp now becomes extinguished, while the opening of the contact 21-21ⁿ interrupts the pickup circuit 45 which was previously closed for relay D at this contact. Relay D will remain energized under these conditions, however, by virtue of its stick circuit. The closing of contact 7-7^r completes a normal control circuit for the reverse magnet 50 R which circuit passes from battery K through wire 9, contact 7-7^r of lever L, lamp H² connected in parallel with resistor J², front contact 13 of relay D, contact 5-5^a of circuit controller G, wire 14, the winding of magnet R, and wires 55 11 and 12 back to battery K. The reverse magnet R, therefore, becomes energized and causes the switch E to move to its reverse position. When the switch reaches its reverse position, contact 5-5^a of circuit controller G becomes 60 opened and contact 5-5^b becomes closed. The opening of contact 5-5^a interrupts the circuit which was previously closed for magnet R, whereupon this magnet becomes deenergized and cuts off the supply of fluid pressure to the switch operating mechanism M. The closing of contact 65 5-5^b of circuit controller G completes a reverse indication circuit including lamp H², which circuit may be traced from battery K through wire 9, contact 7-7^r of lever L, the filament of lamp 70 H² connected in multiple with resistor J², front contact 13 of track relay D, contact 5-5^b of circuit controller G, and wire 12 back to battery K. The indication lamp H², therefore, becomes lighted to indicate that the switch occupies its 75 full reverse position. The movement of the

switch to its reverse position also opens contact 45-45^a of circuit controller G and closes contact 45-45^b. When contact 45-45^b becomes closed, it will complete the pickup circuit for relay D including this contact, but since this relay is already energized by virtue of its stick circuit, the closing of this pickup circuit will have no effect on the remainder of the apparatus.

5 It should be pointed out that while the circuit over which the reverse magnet R becomes energized during movement of the switch to its reverse position under the conditions just described includes lamp H² connected in multiple with resistor J², the lamp H² will not become lighted under these conditions because the resistance of the reverse magnet R is too high to permit sufficient current to flow in the lamp. The function of the resistor J² is to prevent the operator from losing control of the switch in the event that the lamp H² burns out.

10 It should also be pointed out that if, when the switch occupies its reverse position, it should creep away from this position for any reason due, for example, to misadjustment of the biasing means of the mechanism M, contact 5-5^a will 15 become closed and will reestablish the circuit previously traced for the reverse magnet R, thus causing the switch to be immediately restored to its reverse position.

15 When the switch has been moved to its reverse position in the manner just described and it is 20 desired to restore it to its normal position, lever L is restored to its normal position. Under these conditions, as soon as the lever is moved away from its reverse position, the reverse indication 25 circuit becomes interrupted at contact 7-7^r of lever L, thus causing lamp H² to become extinguished, and when the lever reaches its normal position, the resultant closing of contact 7-7ⁿ of lever L completes a normal control circuit 30 for the normal magnet N passing from battery K through wire 9, contact 7-7ⁿ of lever L, the filament of lamp H¹ connected in multiple with resistor J¹, front contact 10 of track relay 35 D, contact 6-6^b of circuit controller G, the winding of normal magnet N, and wires 11 and 12 back to battery K. The normal magnet N, 40 therefore, becomes energized and causes the switch to move to its normal position. When the switch reaches its full normal position, contact 6-6^b of circuit controller G opens and deenergizes magnet N, and contact 6-6^a of circuit controller G closes and completes the previously 45 described indication circuit for lamp H¹. Lamp H¹ then becomes lighted to indicate that the switch 50 occupies its full normal position. The movement of the switch to its full normal position also reestablishes the pickup circuit for relay D including 55 contact 45-45^a of circuit controller G.

60 It should be pointed out that while the circuit over which the normal magnet N becomes energized during the movement of the switch to its normal position under the conditions just described includes lamp H¹ and resistor J¹ connected in multiple, lamp H¹ will not become 65 lighted because the resistance of the normal magnet is too high to permit sufficient current to flow in the lamp H¹. It should also be pointed out that the function of the resistor J¹ is to prevent the operator from losing control of the 70 switch in the event that the lamp H¹ burns out.

75 It should further be pointed out that if, when the switch occupies its normal position, the switch should creep away from this position for any reason, the resultant closing of contact 75

6—6^b of circuit controller G will reestablish the energizing circuit described above for the normal magnet, and will thus cause the switch to be immediately restored to its normal position.

5 We will now assume that the switch occupies its normal position and that a train trails the switch. Under these conditions, as soon as the train passes the insulated joint 2 which is disposed adjacent the one switch point, track relay 10 D will become deenergized by virtue of the train shunt, and will interrupt its own stick circuit as well as all of the previously described control and indication circuits. The interruption of the indication circuit for lamp H¹ will cause this lamp 15 to become extinguished so that both lamps H¹ and H² will then be extinguished. The engagement of the train wheels with the switch points will move the switch points toward their reverse positions, and during the first half of this movement the biasing means will exert a force on the switch points which opposes their movement. However, as soon as the switch points pass their mid stroke positions, the biasing means will then 20 become effective to aid the movement of the switch points, and will thus cause the switch points to move to their full reverse positions with a snap action. When the train which has just 25 trailed the switch departs from section B—C, the train shunt which caused relay D to become deenergized will be removed, but relay D will remain deenergized until lever L is moved to the 30 position corresponding to the new position of the switch, and as long as relay D remains deenergized, both lamps H¹ and H² will remain extinguished, and the switch will remain in its reverse position. It follows, therefore, that, if the 35 operator now wishes to regain control of the switch, it will be necessary for him to move lever L to its reverse position. As soon as he does 40 this, the pickup circuit for relay D including reverse contact 21—21^r of lever L and contact 45—45^b of circuit controller G will become closed, and relay D will then pick up and close its stick circuit. The picking up of relay D will 45 also complete the reverse indication circuit for lamp H², and this lamp will, therefore, become lighted to indicate that the switch and lever now both occupy their reverse positions. After relay D has once picked up, if the operator then wishes 50 to restore the switch to its normal position, he may do so by restoring lever L to its normal position. The operation of the apparatus under these conditions is identical with that which has 55 already been described and need not, therefore, be repeated here.

When the switch occupies its reverse position and a train trails the switch, the operation of the apparatus will be similar to that just described when the switch occupies its normal position and a train trails the switch. It is believed, therefore, that this latter operation will be apparent from an inspection of the drawing without further description.

Referring now to Fig. 2, we have here shown another form of apparatus for accomplishing the same results as are accomplished by means of the apparatus shown in Fig. 1, but which introduces less resistance in the pickup circuit for the track relay. As here shown, the track 65 relay D is controlled by a relay P which latter relay, in turn, is controlled jointly by the lever L and the circuit controller G. Relay P is provided with one pickup circuit which is closed when and only when lever L and switch E both 70 occupy their normal positions, and which passes

from battery K through wires 64 and 65, contact 45—45^a of circuit controller G, wire 66, the winding of relay P, wire 67, contact 21—21ⁿ of lever L, and wire 68 back to battery K. Relay P is also provided with another pickup circuit 5 which is closed when and only when lever L and switch E both occupy their reverse positions, and which passes from battery K through wires 64 and 69, contact 21—21^r of lever L, wire 67, the winding of relay P, wire 66, contact 45—45^b of 10 circuit controller G, and wires 70 and 68 back to battery K. It will be apparent, therefore, that with the apparatus constructed as shown in Fig. 2, relay P will be energized when and only 15 when the switch and lever both occupy corresponding extreme positions.

Relay D is provided with a pickup circuit which is closed when and only when relay P is energized, and which passes from battery 3 through rail 1^a, wires 56 and 71, front contact 12 of relay 20 P, wires 73 and 60, the winding of relay D, wire 61, and rail 1 to battery 3. Relay D is also provided with a stick circuit which is identical with the stick circuit previously traced in connection 25 with Fig. 1.

It will be apparent, therefore, that with the apparatus constructed as shown in Fig. 2 whenever relay D has once been energized, it will subsequently remain energized until a train enters section B—C whereupon this relay will then become deenergized. It will also become apparent that, when this relay once becomes deenergized, it will subsequently remain deenergized until the train departs from section B—C, whereupon this 30 relay will then become energized if relay P is 35 energized, which latter relay, as pointed out hereinbefore, will be energized if and only if the switch and lever occupy corresponding extreme positions.

The remainder of the apparatus shown in 40 Fig. 1 is similar to that shown in Fig. 2 and need not, therefore, be described further.

It will be seen from the foregoing that we have provided means for controlling the switch mechanism M in such manner that, if the switch 45 is trailed, it will remain in its trailed position until the control lever is moved to a position corresponding with the new position of the switch after which the switch may be restored to its original position by restoring the control lever 50 to its original position.

Although we have herein shown and described only two forms of apparatus for controlling railway switches embodying our invention, it is understood that various changes and modifications 55 may be made therein within the scope of the appended claims without departing from the spirit and scope of our invention.

Having thus described our invention, what we claim is:

1. In combination, a stretch of railway track provided with a railway switch having normal and reverse positions, a switch operating mechanism operatively connected with said switch, said switch operating mechanism being provided with 65 means for biasing the switch to its nearest extreme position and with a normal and a reverse magnet and being effective for moving the switch to its normal position or its reverse position according as said normal or said reverse magnet is 70 energized, a manually operable lever having normal and reverse positions and provided with normal and reverse contacts, a circuit controller operatively connected with said switch, said circuit controller being provided with a first contact 75

which is closed when the switch occupies any position but its normal position, with a second contact which is closed when the switch occupies any position but its reverse position, with a third contact which is closed when and only when the switch occupies its normal position, with a fourth contact which is closed when and only when the switch occupies its reverse position, with a fifth contact which is closed when and only when the switch occupies its normal position, and with a sixth contact which is closed when and only when the switch occupies its reverse position, a track section formed in said stretch and extending in opposite directions from said switch, a track relay including the rails of said track section, a normal contact of said lever and said fifth contact of said circuit controller, a second pickup circuit for said track relay including the rails of said track section, a reverse contact of said lever, and said sixth contact of said circuit controller; a stick circuit for said track relay including its own front contact and the rails of said section; two indication lamps, a circuit for the normal magnet including a normal contact of said lever, one of said indication lamps, a first front contact of said track relay, and said first contact of said circuit controller, a circuit for the reverse magnet including a reverse contact of said lever, the other indication lamp, a second front contact of said relay, and said second contact of said circuit controller; a normal indication circuit including a normal contact of said lever, said one indication lamp, said first front contact of said track relay, and said third contact of said circuit controller, and a reverse indication circuit including a reverse contact of said lever, said other indication lamp, said second front contact of said relay, and said fourth contact of said circuit controller.

2. In combination, a stretch of railway track provided with a railway switch having normal and reverse positions, a switch operating mechanism operatively connected with said switch, said switch operating mechanism being provided with means for biasing the switch to its nearest extreme position and with a normal and a reverse magnet and being effective for moving the switch to its normal position or its reverse position according as said normal or said reverse magnet is energized, a manually operable lever having normal and reverse positions and provided with normal and reverse contacts, a circuit controller operatively connected with said switch, said circuit controller being provided with a first contact which is closed when the switch occupies any position but its normal position, with a second contact which is closed when the switch occupies any position but its reverse position, with a third contact which is closed when and only when the switch occupies its normal position, with a fourth contact which is closed when and only when the switch occupies its reverse position, a track section formed in said stretch and extending in opposite directions from said switch, a track relay, a first pickup circuit for said track relay including the rails of said track section, a normal contact of said lever and said third contact of said circuit controller, a second pickup circuit for said track relay including its own front contact and the rails of said section; a stick circuit for said track relay including a reverse contact of said lever, and said fourth contact of said circuit controller; a circuit for the normal magnet including a normal contact of said lever, one of said indication lamps, a first front contact of said track relay, and said first contact of said circuit controller, a circuit for the reverse magnet including a reverse contact of said lever, the other indication lamp, a second front contact of said relay, and said second contact of said circuit controller; a normal indication circuit including a normal contact of said lever, said one indication lamp, said first front contact of said track relay, and said third contact of said circuit controller, and a reverse indication circuit including a reverse contact of said lever, said other indication lamp, said second front contact of said relay, and said fourth contact of said circuit controller.

position, and with a sixth contact which is closed when and only when the switch occupies its reverse position, a track section formed in said stretch and extending in opposite directions from said switch, a track relay, a second relay, a pickup circuit for said track relay including the rails of said section and a front contact of said second relay, a stick circuit for said track relay including its own front contact and the rails of said section, a first pickup circuit for said second relay including a first normal contact of said lever and said third contact of said circuit controller, a second pickup circuit for said second relay including a first reverse contact of said lever and said fourth contact of said circuit controller, two indication lamps, a circuit for the normal magnet including a second normal contact of said lever, one of said indication lamps,

a first front contact of said track relay, and said first contact of said circuit controller, a circuit for the reverse magnet including a second reverse contact of said lever, the other indication lamp, a second front contact of said relay, and said second contact of said circuit controller; a normal indication circuit including said second normal contact of said lever, said one indication lamp, said first front contact of said track relay, and said fifth contact of said circuit controller; and a reverse indication circuit including said second reverse contact of said lever, said other indication lamp, said second front contact of said relay, and said sixth contact of said circuit controller.
